UNITED STATES PATENT OFFICE.

TIMOTHY C. POMEROY, OF MINNEAPOLIS, AND CARL E. JOHNSON, OF ST. PAUL, MINNESOTA, ASSIGNORS OF ONE-THIRD TO JEREMIAH E. MADDEN, OF CHICAGO, ILLINOIS.

LIFTING JACK.

Application filed August 28, 1924. Serial No. 734,730.

This invention relates to new and useful improvements in lifting jacks such as are commonly employed for lifting the wheels or axles of automobiles, trucks, etc., and more particularly relates to such a device of the hydraulic type, using an inelastic fluid such as oil to transmit power in the operation of the jack.

The novel jack featured in this invention is particularly adapted for heavy duty lifting, and it will therefore readily lend itself for use in such places as railroad repair shops where it may be practically employed for lifting heavy loads such as a portion of a locomotive or railroad coach or car. The operating means of the jack preferably consists of a jointed handle having a relatively small pump-rod reciprocally mounted in a section thereof, which, when actuated, functions to move the fluid within the jack during the lifting operation thereof. The operating handle is preferably connected to the lifting head of the jack in order to simplify construction and to provide a simple and convenient means for actuating the valve mechanism mounted therein. The novel valve mechanism is so constructed that, when the handle of the jack is in folded inoperative position all of the valve ports will be closed to prevent leakage of oil from the jack when transported from place to place and, as soon as the handle is unfolded or extended, the valve ports will be automatically opened so that the jack may be operated to lift a load. When it is desired to lower the jack, a slight oscillation or lowering of the handle will permit the fluid to bypass from beneath the piston through the head to the upper side thereof or into the hollow plunger, thereby causing the head and plunger to gradually descend or if desired the load may be held on the jack by slightly raising the handle to close the by-pass. An air vent is provided in the head of the jack to facilitate pumping the fluid from and to the interior of the plunger, through the head to the under side of the plunger. The opening and closing of this vent is also controlled by the simple manipulation of the operating handle. The jack is also provided with a safety means which automatically functions to permit escape of the fluid should the jack accidentally or inadvertently be overloaded.

The object therefore of the invention is to provide an improved jack.

A further and more specific object of the invention is to provide a hydraulic jack of simple and inexpensive construction which may readily be carried from place to place, and is capable of operation with a minimum amount of energy and at the same time will be positive and efficient in its performance.

Other objects of the invention will appear from the following description and the accompanying drawings and will be pointed out in the annexed claims.

In the drawings there is disclosed a structure designed to carry out the various objects of the invention but it is to be understood that the invention is not confined to the exact features shown, as various changes may be made within the scope of the claims which follow.

In the drawings:

Figure 1 is a vertical sectional view of the improved jack;

Figure 2 is a plan view of Figure 1, showing the handle extended and partially in section, and also showing the jack with the lifting bracket removed;

Figure 3 is a horizontal sectional view on the line 3-3 of Figure 1 with the lifting bracket removed showing the preferred manner of connecting the operating handle to the head;

Figure 4 is a detail sectional view on the line 4-4 of Figure 3, showing the means provided for by-passing the fluid from beneath the plunger end to the upper side thereof as when lowering the plunger;

Figure 5 is a similar view on the line 5-5 of Figure 3, showing the air vent communicating with the upper portion of the plunger;

Figure 6 is an enlarged detail sectional view showing the preferred form of packing employed between the upper end of the cylinder and the plunger, and also showing the means provided for limiting the upward movement of the plunger;

Figure 7 is a detail sectional view on the line 7-7 of Figure 2;

Figure 8 is an enlarged detail sectional view on the line 8-8 of Figure 1;

Figure 9 is a horizontal sectional view on the line 9-9 of Figure 1, showing only the lifting head and the tapered valve.

mounted therein, the valve being shown in full lines; and

Figure 10 is a similar view on the line 10—10 of the same figure.

- 5 In the selected embodiment of the invention here shown there is illustrated a jack comprising a cylinder 10 mounted in a suitable base 11. A plug 12 is preferably fitted into the lower end of the cylinder in order 10 to provide a rigid oil-tight mounting when seated in the base and to prevent the cylinder walls from contracting when subjected to severe side strains. A hollow sleeve or plunger 13 is reciprocally mounted within 15 the cylinder, and as shown in Figure 1 the lower end of this sleeve is closed by means of a shouldered disc or plate 14. A packing cup 15 of suitable material is seated against this plate and is tensionably held in contact 20 with the walls of the cylinder by means of a cup-shaped retaining member 16 mounted therein. A washer 17 is seated against the member 16 and this washer is apertured to receive the threaded ends of an intake tube 25 18 and a discharge tube 19, arranged in spaced parallel relation within the hollow plunger 13. The upper ends of these tubes are secured to a lifting head 21 by suitable means such as the threads 22. The lifting head 21 is preferably provided with an annular shoulder 23, adapted to be seated against the upper end of the hollow plunger 13. A threaded nut 24 is mounted on the lower end of the discharge tube 19 and a 30 cap 25 on the lower end of the intake tube 18, and when these two are tightened the head 21, plunger 13, retaining member 16, and the washer 17 will be securely clamped together for operation as a unit.
- 35 40 A feature of this invention resides in the novel means provided for limiting the upward movement of the plunger, and such means preferably consists in the provision of a suitable stop provided adjacent the upper end portion of the cylinder. As shown in Figure 1, a packing nut 26 is provided at the upper end of the cylinder and within this packing nut the usual packing 27 is provided. An annular ring or detent 28 is 45 seated against the end of the cylinder beneath the packing 27 and this ring overhangs the bore of the cylinder and thereby functions to provide a limit stop for the upward movement of the plunger. As shown in 50 this figure, the major portion of the plunger 13 is preferably reduced in diameter in order to provide an annular shoulder 29 adjacent the lower end portion thereof. This shoulder is adapted to engage the stop ring 28 when the plunger reaches the limit of its 55 upward movement as clearly shown in Figure 6. It will also be noted by referring to Figure 1 that means are provided for returning to the interior of the plunger 13 any oil which may pass by the packing cup 60

15 and enter the annular space around the plunger between the shoulder 29 and detent or stop ring 28, caused by the high pressure beneath the plunger when the jack is in operation. Such means preferably consists in 70 providing a plurality of apertures 31 in the wall of the hollow plunger 13 slightly below the annular shoulder 29. Small ducts or grooves 32 in the outer wall of the plunger connect these apertures with the annular 75 space around the plunger above the shoulder 29, so that any oil, which might leak by the packing cup 15 from beneath the plunger and enter the annular space will be bypassed through the grooves 32 and apertures 80 31 into the interior of the plunger as it ascends, thereby eliminating the objectionable feature of the oil leaking out of the cylinder when the jack is used for lifting extremely heavy loads, which is a common occurrence with hydraulic jacks of ordinary construction. This, therefore, is an important feature of the invention as it practically renders the jack leak-proof.

85 As shown in Figure 1, the intake tube 18 is provided with an intake port 33 adjacent the lower end-portion thereof which is in communication with the interior of the plunger 13. A port 34 having a ball check valve 35 of ordinary construction arranged 90 therein, is provided in the lifting head 21, and this port connects the upper end of the intake tube 18 with a horizontal duct 36, having one end in communication with a similar upright port 37 which downwardly 95 leads therefrom and is in connection with the upper end of the discharge tube 19. A spring-actuated check valve 38 is mounted 100 in the horizontal duct 36, and this valve functions to prevent the oil pumped into the tube 19, from flowing back into the intake tube 18 when the jack is being operated to lift a load. Threaded plugs 39 and 41 are 105 mounted in the head 21 and function to close the ends of the port 34 and duct 36, respectively in order to facilitate assembling 110 of the valves 35 and 38, mounted therein.

115 The means provided for by-passing the oil from beneath the plunger back into the interior of the plunger, in the operation of lowering the jack, preferably consists in the provision of a tapered valve plug 42 seated in a correspondingly tapered bore 43 provided in a boss 40 preferably integrally formed on one side of the lifting head 21 120 as shown in Figures 1 and 3. This valve plug 42 also functions as a means for pivotally connecting to the jack, the jack handle and pumping means, which will subsequently be described. Referring to the 125 above figures, it will be noted that the horizontal duct 36 extends beyond the upright port 34 and is in communication with an annular groove 44 provided in the central portion of the body of the tapered plug 42. 130

An aperture 45 is drilled through the plug in alinement with the annular groove 44, and this aperture is in communication with a conduit 46 provided in the plug, as clearly shown in Figure 3. The other end of the conduit 46 terminates in a hub 47 which is preferably integrally formed on the plug and is arranged at right angles thereto. This hub is suitably threaded to receive one end of a tube or pipe 48 comprising the intermediate section of the handle. The tapered plug 42 is yieldably retained in its tapered seat by means of a compression spring 49 coiled about the reduced end portion 51 thereof. This spring preferably has one end bearing against a washer 52 which is seated against the annular face 53 provided round the reduced end-portion of the tapered bore 43. The other end of the spring is seated in a cap 54 which is prevented from outward movement upon the reduced end portion 51 of the plug by means of a pin 55. The reduced end portion 51 is preferably provided with a flattened surface 50 as shown in Figure 7 to prevent the cap 54 from rotating thereon. The cap 54 is of such length as to normally be out of engagement with the face 53 and functions to provide a shield or closure for the spring 49 and washer 52 thereby to present a neater appearance to the jack. The cap, however, may also function as a means for limiting the axial movement of the plug 42, should the pressure within the conduit 46 and groove 44 become so high that it would tend to unseat the plug from its tapered seat, as will hereinafter be more fully described.

Referring to Figure 9, it will be seen that the upright port 37 is in communication with a relatively smaller port 56 by means of a duct 57. The port 56 has one end leading to the tapered bore 43 of the tapered plug 42. Similarly, the port 34 is connected to the tapered bore 43 by means of a duct 58 and a port 59 as shown in Figure 10. The ports 56 and 59 are preferably horizontally arranged in spaced parallel relation in the lifting head 21 as particularly shown in Figure 4. In order to facilitate construction the ports 56 and 59 are preferably drilled from the outside of the lifting head and it is therefore necessary that their outer ends be suitably sealed by such means as the threaded plugs 61. In order to establish communication between the ports 56 and 59, a notch or recess 62 is cut in one side of the tapered plug 42 in alinement with the two ports, and when the plug 42 is positioned as shown in Figure 4, communication between the two ports will be cut off, the notch 62 registering with the lower port 59 only. When the jack is being operated to lift a load the tapered plug 42 will be positioned as shown in Figure 4, and when it is desired to lower the jack, the plug will be

rotated in its seat until the notch 62 is brought into registration with the two ports 56 and 59 thereby permitting the oil to flow from the upright port 37 through the duct 57, port 56 and notch 62, port 59, duct 58, 70 upright port 34, and through the intake pipe or tube 18 back to the interior of the plunger. By this simple valve mechanism, therefore, the operator will have complete control of the raising and lowering of the jack by 75 simply rotating the plug 42 in its seat.

Another feature of this invention resides in the novel means provided for pumping the oil from the interior of the hollow plunger to beneath the plunger in the lifting 80 operation of the jack. Such means preferably consists of a reciprocating displacement pump mounted in a section of the handle, which handle is preferably composed of two sections in order that it may be conveniently 85 folded for packing in a small place, and also for the convenience in operation. This pump consists of a pump-rod 63 which is loosely fitted within a hollow tube 64 as particularly shown in Figure 8. A knurled sleeve 65 is secured to one end of the tube 64 by means of threads 66, and this sleeve is bored to receive a packing gland 67 which has provided thereon a shoulder 68 adapted to be seated against a complementary shoulder provided 90 in the bore of the sleeve 65. A suitable packing 69 is interposed, in the usual manner, between the upper end of the stationary gland 67 and the lower end of a movable gland 71 mounted in the enlarged bore 72 100 of the sleeve as shown in Figure 1. The upper end of the sleeve is provided with a reduced end portion 73 which is threaded to receive a nut 74. This nut functions to tightly force the movable gland 71 against 105 the packing 69 thereby tightly compressing the packing against the pump rod 63. A lock spring 75 is preferably interposed between the upper end of the reduced end portion 73 of the sleeve and the inner face 110 of the nut 74 and this spring functions to lock the nut in adjusted position. An operating handle or grip 76 is secured to the upper end of the pump rod 63 to provide means whereby it may be conveniently 115 operated, the knurled nut 65 also functioning as a hand grip to support the pump handle while in use. By means of the novel construction above-described, it will be seen that should the pressure in the tube 64 be 120 come excessive the gland 67 which normally is stationary will be forced against the packing 69 which in turn will be forced against the movable gland 71 and the pump rod 63 125 with the result that it will be impossible for any oil to escape therethrough.

It will also be noted by referring to Figures 1 and 8 that the pump rod 63 is loosely fitted within the hollow tube 64 and therefore does not come in contact with the 130

- walls thereof. As a result of this construction, an annular space is provided between the pump rod and the inner wall of the tube 64 and this space is normally filled with the oil or other fluid used in the operation of the jack. A small head 77 is preferably secured to the lower end of the rod 63, this head merely functioning to prevent the rod from being withdrawn from the tube 64.
- 10 As shown in Figure 8, the head 77 is preferably flattened on opposite sides in order to allow the fluid to freely pass thereby.
- As hereinbefore stated, the operating handle of this novel jack is preferably constructed in two sections, the pump section and an intermediate section connecting the pump section to the lifting head of the jack. The two handle sections are pivotally connected together by means of an oil-tight joint similar in construction to the tapered plug valve connecting the intermediate handle section to the lifting head of the jack as shown in Figure 3. This joint preferably comprises a body 78 having a tapered bore 79 provided therein adapted to receive a correspondingly tapered plug 81 as shown in Figure 2. The means provided for retaining the plug 81 in its seat is similar to that shown and described with reference to the tapered plug 42, and like parts will therefore be referred to by like numerals. Similar to the plug 42, the plug 81 is provided with an annular groove 82 which is preferably in alignment with the tube 64 of the pump section of the handle, which tube is secured to the body 78 of the joint by means of the threads 83. An aperture 84 is drilled through the plug 81 and this aperture is in communication with a port 85 also provided in the plug and which port terminates in a right-angled boss 86 threaded to receive one end of the pipe 48 comprising the intermediate handle section. By thus constructing the handle of two sections, the handle may readily and conveniently be folded to lie substantially parallel to the cylinder of the jack, thereby permitting the jack to be packed away in a small space, such for instance as the usual toolbox of an automobile or truck. When the jack is in use, the handle may be extended its full length, thereby permitting the operator to stand in an erect position when operating the jack, if he desires.
- 55 A demountable lifting step 87 is preferably provided and this step has formed thereon an undercut flange 88 adapted to engage a similar undercut portion 89 of the lifting head 21 when positioned thereon as shown in Figure 1. A lug 91 is also provided on the step 87 and this lug is adapted to engage the opposite side of the head 21, thereby to securely lock the step to the lifting head 21 when the step 87 is being used to lift the load. When the step 87 is thus

being used to lift a load, the lug 91 bearing against the side of the lifting head 21, will be under compression and the upper portion 92 of the step will be under tension as a result of the undercut flange 88 engaging the undercut portion 89 of the head, thereby securely locking the step to the lifting head of the jack. If desired, the lifting step 87 may be removed from the head of the jack by simply lifting the projecting lower end 87 thereof, and when thus removed the jack may be used without the step by placing the jack directly beneath the load and allowing the upper face of the head 21 to contact therewith. A filler plug 93 is provided in the head 21 through which oil may be introduced into the interior of the hollow plunger 13.

In the operation of hydraulic jacks, it is necessary that means be provided whereby air may be admitted to the interior of the oil chamber or reservoir in order that the pump may properly function without the danger of building up a vacuum or a high pressure therein which would interfere with the operation of the jack and would tend to render it inoperative. Means are therefore provided in this novel jack whereby air may be drawn into the hollow plunger 13 when the oil is being pumped therefrom into the cylinder 10 beneath the plunger. Such means preferably consists in the provision of an inclined passage 94 provided in the lifting head 21 which establishes communication between the interior of the hollow plunger 13 and the tapered seat 43 of the lifting head. A vent 95 is provided in the lower wall of the hub 40 and this vent is in registration with a semi-annular groove 96 provided in one side of the tapered plug 42 as particularly shown in Figure 5. The passage 94, vent 95 and the groove 96 are so arranged as to be in alignment with one another, thereby providing a communicating passage leading from the interior of the plunger 13 to the exterior thereof. When the oil level in the hollow plunger 13 is lowered by the pumping of the oil therefrom into the lower portion of the cylinder beneath the plunger, air will be drawn into the plunger through the vent 95, thereby preventing the formation of a vacuum within the upper end of the plunger, which would tend to render the jack inoperative. Conversely, when the oil is returned from the cylinder, beneath the plunger, back to the interior of the plunger rod 13, the air drawn into the plunger above the oil level will be expelled therefrom through the passage 94, groove 96, and vent 95 to the atmosphere.

In the operation of this novel jack, the plunger and cylinder thereof will first be filled with a suitable liquid such as oil and the pump rod 63 reciprocated within the

handle pipe section 64 until the oil is drawn into the tube as shown in Figure 1, after which the jack is ready for service. When desiring to lift a load, the handle sections 5 are extended or unfolded to substantially a horizontal position as shown in Figures 4 and 5, in which position the port 56 leading from the tapered bore 43 in the lifting head to the upright port 37 will be closed as particularly shown in Figure 4, thereby preventing the oil pumped into the lower portion of the cylinder from returning through the ports 56 and 59 to the interior of the plunger. As the pump rod 63 is withdrawn 10 from the tube or pipe 64, oil will be drawn from the interior of the plunger through the port 33, intake tube 18, port 34, around the valve 35, into the duct 36, through the tapered plug 42 and into the intermediate pipe 20 or handle section 48, through the port 85 in the plug 81, and into the tube 64 of the pump. As the pump rod 63 is downwardly forced into the tube 64, the oil will be displaced thereby and will therefore be forced 25 back into the intermediate handle section 48 through the tapered plug 42 and into the horizontal duct 36 in the lifting head, thereby seating the valve 35 and opening the valve 38 after which it will be downwardly 30 forced through the upright port 37 and into the discharge pipe 19 into the lower portion of the cylinder beneath the plunger, with the resultant raising of such plunger. Continued reciprocation of the pump rod 63 35 will cause the oil to be pumped from the interior of the plunger to the lower portion of the cylinder beneath the plunger until the load has been lifted to the desired height. When it is desired to lower the jack, it is 40 only necessary to slightly lower the intermediate handle section 48 from a horizontal position until the recess 62 in the plug 42 is brought into registration with the two ports 56 and 59, thereby establishing communication between the lower portion of the cylinder and the interior of the plunger. Owing to the high pressure of the oil beneath the plunger, caused by the load resting thereon, the oil will be upwardly forced 45 50 through the discharge pipe 19, and into the upright port 37, through the connecting duct 57, port 56, recess 62, port 59, connecting duct 58 and into the upright port 34, from whence it will flow downwardly 55 through the intake pipe 18, through the port 33 and into the interior of the plunger, thereby allowing the plunger, and therefore the lifting head to descend to normal or inactive position.

60 Referring to Figure 4, it will be noted that the connecting ducts 57 and 58 are so arranged in the lifting head that the oil flowing from the cylinder back to the interior of the plunger will not pass through 65 either of the valves 38 and 35. It will also

be noted that the connecting duct 58 communicates with the upright port 34 at a point below the valve, thereby allowing the oil to enter the intake pipe 18 beneath the valve 35, with the result that the valves remain seated during the lowering operation of the jack. 70

Another feature of this invention resides in the novel construction of the pivotal connection between the intermediate handle section 48 and the lifting head of the jack which connection serves a dual purpose. In addition to providing a pivotal connection between the handle and the jack, it also functions as a safety valve, should the effective pressure in the jack become excessive, as in the case the plunger has reached the top of its stroke with the shoulder 29 abutting the stop ring 28 and the operator continues to manipulate the pump rod 63. 75 Referring to Figure 3 it will be noted that a clearance is provided between the face 53 of the boss 40 and the adjacent marginal edge of the cap 54, when the tapered plug 42 is in normal seated position as here shown. Thus, should an excessive pressure be built up in the plug 42, and therefore in the jack and handle sections, such pressure will cause the tapered plug 42 to be 80 unseated or to be axially moved in its tapered seat or bore 43 against the tension of the spring 49. Such axial movement of the plug 42 will allow a portion of the oil to escape through the gap thus provided between the peripheral surface of the plug and the wall of the tapered bore 43, thereby protecting the jack against damage which might occur from excessive oil pressure. 85 90

95 From the foregoing, therefore, it will be seen that this novel jack is substantially fool-proof. Its construction is such that it may be readily and conveniently operated from any position of the operator, and is also such that it will be positive and efficient in operation and performance. 100 105

Having thus described our invention what we claim as new and desire to secure by Letters Patent, is:

110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

1. A lifting jack comprising in combination, a cylinder, a hollow plunger therein, a lifting head on the upper end of the plunger and the lower plunger-end effecting a substantially fluid-tight fit with the inner wall of the cylinder, an inelastic fluid within the plunger, pump means for forcing the fluid from the interior of the plunger into the lower portion of the cylinder beneath the plunger to raise it, a by-pass for returning the fluid from the cylinder to the plunger, a portion of the plunger wall being reduced exteriorly thereof to provide an annular space between plunger and cylinder walls, grooves in the enlarged wall portion of the plunger communicating with said annular space, and apertures connecting said

- grooves with the interior of the plunger, whereby fluid escaping into the annular space from beneath the plunger will be returned to the interior of the plunger.
- 5 2. A lifting jack comprising in combination, a cylinder, a hollow plunger therein, a lifting head on the upper end of the plunger and the lower plunger-end effecting a substantially fluid-tight fit with the inner 10 wall of the cylinder, an inelastic fluid within the plunger, pump means for forcing the fluid from the interior of the plunger into the lower portion of the cylinder beneath the plunger to raise it, means for by-passing 15 the fluid from the cylinder to the interior of the plunger to lower the latter, a portion of the plunger wall being reduced exteriorly thereof to provide an annular space between plunger and cylinder walls, grooves 20 in the enlarged wall portion of the plunger communicating with said annular space, apertures connecting said grooves with the interior of the plunger, whereby fluid escaping into the annular space from beneath the plunger will be returned to the interior of the plunger, an annular shoulder on the 25 plunger wall exteriorly thereof and adjacent to its lower end, an abutment ring de-
- mountably seated upon the upper end of the cylinder and overhanging the bore thereof, 30 and adapted to be engaged by said annular shoulder to provide a limit stop for the upward movement of the plunger.
3. A lifting jack comprising in combination, a cylinder, a hollow plunger operable 35 therein, a lifting head on the upper end of the plunger and the lower plunger-end effecting a substantially fluid-tight fit with the inner wall of the cylinder, an inelastic fluid within the plunger, means to pump the 40 fluid from the plunger and force it into the lower portion of the cylinder beneath the plunger to raise it, means for returning the fluid from the cylinder to the interior of the plunger to lower the latter, stop means on the exterior of the plunger to limit its raising, the exterior of the plunger wall having a duct therein communicating with an aperture through said wall whereby any fluid 45 escaping above the lower plunger-end returns to the plunger interior, said aperture being located below said stop means.

In witness whereof, we have hereunto set our hands this 23rd day of May 1924.

TIMOTHY C. POMEROY.
CARL E. JOHNSON.
